WILLIAM ISAAC RAVERT, OF HAZLETON, PENNSYLVANIA, ASSIGNOR TO STANDARD AUTOMATIC MACHINE COMPANY, OF PITTSBURGH, PENNSYLVANIA, A CORPORATION OF DELAWARE.

MOISTENER ATTACHMENT FOR TOBACCO-VENDING MACHINES.

1,280,298.

Specification of Letters Patent.

Patented Oct. 1, 1918.

Application filed August 24, 1917. Serial No. 188,009.

To all whom it may concern:

Be it known that I, WILLIAM I. RAVERT, a citizen of the United States, residing at Hazleton, in the county of Luzerne and State 5 of Pennsylvania, have invented a new and useful Moistener Attachment for Tobacco-Vending Machines, of which the following is a specification.

This invention has reference to moistener attachments for tobacco vending machines and is intended particularly for use in connection with machines for vending cigars.

The object of the invention is to produce a moist atmosphere in the immediate neighborhood of the cigars, especially when the latter are in the box.

In accordance with the invention, a container for water is mounted high in the vending machine and is provided with capillary means whereby water in the container, which container may underride the installed box of cigars, is raised to a greater height than the top of the installed box of cigars and is there presented to the air so that by evaporation the air becomes moistened and in its natural fall contacts with the cigars in the box, thus keeping them in a suitably moist condition. The invention provides for regulation of the degree of humidity so that if there be a tendency for the cigars to become too moist, such tendency may be checked; or, if there be a tendency for the cigars to become too dry, the humidity of the air in the immediate neighborhood of the 35 cigars may be increased.

The invention will be best understood from a consideration of the following detailed description, taken in connection with the accompanying drawings forming part of this specification, with the further understanding that, while the drawings show a practical form of the invention, the latter is not confined to any strict conformity with the showing of the drawings but may be changed and modified so long as such changes and modifications come within the scope of the appended claims.

In the drawing:

Figure 1 is an upright front to rear section of a vending machine embodying the invention, the section being taken about mid-way of the width of the machine;

Fig. 2 is a section on the line 2—2 of Fig. 1;

Fig. 3 is a perspective view of the moistener separate from the vending machine.

Referring to the drawing, there is shown a casing 1, which may be considered as constituting the casing of a vending machine, having vending apparatus 2 indicated in Fig. 1 without any attempt to show details thereof, since the vending apparatus *per se* forms no part of the invention. The vending apparatus is so arranged as to discharge cigars into a receptacle 3 near the bottom of the casing within reach of the purchaser and suitable supports 4 are provided within the casing for supporting a box of cigars simply indicated in Fig. 1 by dotted lines at 5. In a machine of the character thus outlined, the box 5 of the cigars is placed at an incline so that the end of the box, which, in the installed position constitutes the rear end, is considerably elevated above the front end and is close to the top of the interior of the casing.

The moistening apparatus comprises a container 6 designed to receive a quantity of water indicated in Figs. 1 and 2 at 7. The container 6 is long enough to reach across the casing 1 within the upper portion thereof and may be of a size to fit either snugly or loosely crosswise of the casing, suitable brackets 8 fast to the back and sides of the casing serving as supports for the container 6.

The casing 1 has a top portion 9 which may be hinged at 10 to the body of the casing, thus permitting access to the interior of the casing by turning the top portion 9 about the hinge 10. This exposes the installed container 6 and the box 5 of cigars or permits the installation of the container and box. The brackets 8 are so positioned that the container 6 is in underriding relation to the box 5 when both are in place within the casing.

At each end of the container there is an upstanding extension 11 having a wall 12 entering the corresponding portion of the container to the body thereof and provided with a small passage 12^a of any suitable shape permitting access of water from the body of the container 6 to the bottom portion of each of the upstanding parts 11. The wall 12 of each upstanding portion 11 is continued to the top of the upstanding portion and is formed with an upright slot or recess

13 which, in the particular showing of the drawing, is open at the top, each extension 11 being also open at the top. In each extension 11 is lodged a wick or block 14 of asbestos or some other suitable material of capillary nature capable of elevating water from the bottom portion of the container 6 to the top of the wick where the water is exposed to air particularly through the slot 13.

10 In order to regulate the area of exposure of the wick 14 to the air, there is provided a slide 15, which may be a metallic slide, and this slide is formed with lips 16 and 17. There is one lip 16 at the top of the slide to 15 serve as a handle, while the other lips 17 are so bent that they may engage the lower wall of the slot 13 and thus hold the slide 15 in different positions of elevation, thereby exposing different areas of the wick 14 within 20 the slot 13 to contact with the atmosphere. In this way, the amount of evaporation which may take place is controllable.

The box 5 enters between the uprights 11 close to them, whereby the evaporating surfaces of the wicks 14 are close to the sides of the box and are arranged higher than the sides of the box at the upper end of the latter. Consequently, the evaporation which may take place correspondingly humidifies 30 the air above the cigar box, and this air is confined more or less to the cigar box and the cigars therein, which are thereby kept in a moist condition and are prevented from becoming too dry.

35 When atmospheric conditions are such that the humidity of the air within the top of the casing is too great, the slide 15 may be raised and the evaporating surface of the wick 14 correspondingly reduced. On the 40 contrary, the lowering of the slide 15 increases the evaporating surface and the humidity of the air may be thereby increased.

In each event, the humidifying of the air 45 is at a high point within the casing and directly opposite the opposite sides of the installed box of cigars at the high point of the latter, so that the moisture is delivered to the cigars in the most direct and efficient 50 manner.

In order to facilitate the introduction of water into the casing 1, a filler 18 is provided at a convenient point.

By providing a water receptacle with rising capillary devices exposed at high points to the atmosphere, the degree of humidity imparted to the atmosphere may be sensibly constant under the prevalent atmospheric condition and may be made to continue during long periods of time without attention. Such a moistening device is far superior to masses of absorbent material in which the amount of moisture progressively decreases and which, unless water be frequently added, 65 soon becomes dry or so deficient in moisture

that the humidifying effect becomes rapidly decreased to a marked degree.

What is claimed is:

1. A moistening means for tobacco vending machines, comprising an elongated receptacle for water, and capillary devices rising therefrom and provided with evaporating surfaces facing each other and spaced apart for location on the opposite sides of a box of cigars lodged in the vending machine 75 over the water receptacle.

2. A moistening means for tobacco vending machines, comprising a water receptacle with up-standing ends rising therefrom, and capillary devices within the ends and entering the water receptacle, said receptacle being of a length between the ends sufficient to receive one end of a box of cigars, and said ends being of a height to rise above the box of cigars, and where so rising above the box 85 of cigars exposing the capillary devices at the faces toward said box of cigars.

3. A moistener attachment for tobacco vending machines, comprising an elongated container for water with uprising ends communicating with the bottom portions of the corresponding ends of the container and open at the upper ends, each uprising portion having the face toward the other uprising portion open, and a wick-like member of 95 capillary characteristics lodged in the upright portion and extending to the bottom thereof with portions exposed to the atmosphere through the open sides of the upright portions to provide evaporating surfaces. 100

4. A moistener attachment for tobacco vending machines, comprising an elongated container for water with uprising ends communicating with the bottom portions of the corresponding ends of the container and open at the upper ends, each uprising portion having a face toward the other uprising portion open, and a wick-like member of capillary characteristics lodged in the upright portion and extending to the bottom 110 thereof with portions exposed to the atmosphere through the open sides of the upright portions to provide evaporating surfaces, said upright portions each having a slide member movable therein over the evaporating 115 surface of the wick.

5. In a vending machine for cigars, a support therein, and a moistening device having a container for water arranged transversely of the support below one end thereof and provided with upstanding ends with capillary conductors of water therein, and said upstanding ends each having the side toward the other open to expose surfaces of the capillary conductors for evaporation of the water carried thereby, the open sides being located on opposite sides of the support at a higher elevation than those portions of the support adjacent to the moistening device. 125

6. A moistener attachment for tobacco 130

vending machines comprising an elongated container for water with upstanding hollow ends each having the wall facing the other end of the container entering the latter with the hollow end communicating with the container through said wall at a low point, and said wall above the container having an elongated slot or opening, and a body of capillary material lodged in the upstanding hollow end and having an evaporating surface presented at the slot in the inner wall of said upstanding end.

7. A moistener attachment for tobacco vending machines comprising an elongated container for water with upstanding ends each having a wall toward the other end entering the container and communicating therewith at a low point, said wall above the

20 container having an elongated slot or opening, and a body of capillary material lodged in the upstanding end and having an evaporating surface presented at the slot in the inner wall of said upstanding end, said container also being provided with a slide in each upstanding end movable up and down therein into varying covering relation to the slot, and the slide and upstanding end having coacting means for holding said slide in different positions of adjustment.

25 In testimony, that I claim the foregoing as my own, I have hereto affixed my signature in the presence of two witnesses.

30 WILLIAM ISAAC RAVERT.
